UNITED STATES PATENT OFFICE.

VALENTINE KERN, OF ERIE, PENNSYLVANIA.

FASTENER.

SPECIFICATION forming part of Letters Patent No. 730,129, dated June 2, 1903.

Application filed December 20, 1902. Serial No. 136,040. (No model.)

To all whom it may concern:

Be it known that I, VALENTINE KERN, a citizen of the United States, residing at Erie, in the county of Erie and State of Pennsylvania, have invented new and useful Improvements in Fasteners, of which the following is a specification.

This invention relates to fasteners; and it consists in certain improvements in the construction thereof, as will be hereinafter fully described, and pointed out in the claim.

More particularly the invention relates to window or door fasteners, and is peculiarly adapted for sash-fasteners.

15 The invention is illustrated in the accompanying drawings, as follows:

Figure 1 shows a side elevation of a fragment in window, a part being broken away and in section to better show construction.

20 Fig. 2 shows a perspective view of the catch. Fig. 3 shows a vertical section of an alternative construction; Fig. 4, a horizontal section of the alternative construction, wherein the device is adapted to a door; Fig. 5, a front elevation of the window with the fastener in place thereon.

25 A marks the window-casing. This is provided with the sockets *a*, the face having the sockets preferably protected by the plate *a'*, having openings to register with the sockets *a*.

The window-sash *B* has the recess *b* arranged in the face opposite the frame or casing. A guide-way *b'* extends into the window-sash from this recess, and an opening *b*² extends through this guideway to the front face of the sash. This opening is preferably covered by a metal plate *b*³, said metal plate being provided with an opening *b*⁹, which extends into the opening *b*². The catch *C* is provided with an end *c*, adapted to enter the socket *a*. It extends back into the guideway *b'* and has an outwardly-extending handle *c'*, which extends through the slot or opening *b*⁹. The neck *c*³ of the handle is proportioned to permit of the handle being extended through the plate *b*³ and then turned so as to bring the catch into line with the opening *b*².

A spring *D* is arranged in the recess *b*. The spring is turned back upon itself, forming a

plate *d*, in which is an opening *d'*, registering with the end of the guideway *b'*. This plate is secured in the recess by the screws *d*². The active part of the spring *d*³ is secured to the catch by means of the shoulders at the sides of the notch *c*³ in the catch *C*. The spring is tensioned to force the end of the catch into the socket *a*. It is preferable to set the plate *b*³ into the sash sufficient depth that the handle *c'* will clear the companion sash in the window.

In the alternative construction shown in Fig. 3 the sash *A'* forms the frame or relatively stationary part to which the relatively movable sash *B'* is to be locked. The recess *b*⁴ and guideway *b*⁵ are cut into the face of the sash opposite the sash *A'*, and the plate *b*⁶ is arranged over the guideway. The other parts of the structure are similar to those shown in Fig. 1. Fig. 4 shows an alternative construction wherein the fastening is adapted to a door. The casing *A*² has the socket *a*³ to receive the end of the catch. The catch *c'* is similar in construction to the catch *C*, except the end *c*⁴ is beveled in the ordinary manner of catches on doors. The door is provided with a recess *b*⁸, in which is a guideway *b*⁷, and this is covered with a plate *b*¹⁰. The spring is the same as the spring shown in Fig. 1 and the parts operate in a manner similar.

75 What I claim as new is—

In a fastener, the combination with a stationary frame; a movable frame to be locked therewith, said movable frame having a recess in the face opposite the stationary frame and a guideway extending therefrom; of a catch extending into the guideway and through the recess; and the spring having the plate with the opening *d'* and the active portion of the spring *d*³ extending therefrom and secured to the catch.

80 In testimony whereof I have hereunto set my hand in the presence of two subscribing witnesses.

VALENTINE KERN.
